[57] CLAIM

The ornamental design for an aerobic exercise platform, as shown and described.

DESCRIPTION

FIG. 1 is a front elevational view of an aerobic exercise platform in accordance with my design;

FIG. 2 is a top plan view thereof;

FIG. 3 is a rear elevational view thereof;

FIG. 4 is a bottom plan view thereof;

FIG. 5 is a right elevational view thereof with the left side elevational view being a mirror image; and,

FIG. 6 is a top plan view of a modified embodiment of the aerobic exercise platform, the remaining views thereof appearing the same as FIGS. 1, 3, 4, and 5 but without the resistance cords.

*Fig.2.**Fig.1.**Fig. 3.**Fig. 4.**Fig. 5.**Fig. 6.*
